CLAIM

The ornamental design for a cleaning utensil holder, as shown and described.

DESCRIPTION

FIG. 1 is a top, front perspective view of a cleaning utensil holder showing my new design;

FIG. 2 is a top, rear perspective view thereof;

FIG. 3 is a bottom, front perspective view thereof;

FIG. 4 is a bottom, rear perspective view thereof;

FIG. 5 is a left side elevational view thereof;

FIG. 6 is a front elevational view thereof;

FIG. 7 is a right side elevational view thereof;

FIG. 8 is a rear elevational view thereof;

FIG. 9 is a top plan view thereof; and,

FIG. 10 is a bottom plan view thereof.

The alternating long and short lines represent contour lines and form part of the claimed design.
